UNITED STATES PATENT OFFICE.

JAMES E. JACKSON, OF LYNN, MASSACHUSETTS, ASSIGNOR TO UNITED SHOE MACHINERY COMPANY, OF PATERSON, NEW JERSEY, A CORPORATION OF NEW JERSEY.

METHOD OF MAKING INSOLES.

1,191,133.

Specification of Letters Patent.

Patented July 11, 1916.

Original application filed September 18, 1911, Serial No. 650,620. Renewed March 5, 1914, Serial No. 822,767. Divided and this application filed October 4, 1915. Serial No. 53,993.

To all whom it may concern:

Be it known that I, JAMES E. JACKSON, a citizen of the United States, residing at Lynn, in the county of Essex and State of Massachusetts, have invented certain new and useful improvements in Methods of Making Insoles; and I do hereby declare the following to be a full, clear, and exact description of the invention, such as will enable others skilled in the art to which it pertains to make and use the same.

This invention relates to a method of making insoles, and more particularly to a method of making reinforced insoles.

15 The novel insole produced by the method hereinafter described, its method of manufacture, and a machine for performing one of the steps in the process of its manufacture, are disclosed in applicant's application for Letters Patent of the United States filed originally September 18, 1911, Serial No. 650,620 and renewed March 5, 1914, Serial No. 822,767 (Patent No. 1,162,721, dated November 30, 1915), from which original 25 application the present application is a division.

In the early life of reinforced insoles the type having the greatest commercial success was the "Gem" disclosed in the patent 30 to Cole No. 575,460, dated January 19, 1897. Later other types of reinforced insoles were developed such as the "Economy" disclosed in the patent to Johnson No. 849,245, dated April 2, 1907, and the "Wonder-Worker"

35 disclosed in the patent to Ryan No. 958,013, dated May 7, 1910, and to some extent in the earlier patents to Krippendorf No. 579,518, dated March 23, 1897, and Bohr No. 878,453, dated February 4, 1908. The

40 "Gem" insole was a better insole than the "Rochester" insole, disclosed in the patent to Moore No. 275,248, dated April 3, 1883, which preceded it, because in the Gem the reinforcing fabric is carried across the 45 feather thus stiffening this exceedingly flexible portion of the insole and preventing its becoming curled up under the upper in the lasting and subsequent operation on the shoe. For this reason, also, the commercial 50 supremacy of the Gem insole has been generally maintained since the introduction of the Economy type of reinforced insole because this type is open to the same criticism as the Rochester insole, that is, an un-

reinforced feather is used, which is a serious 55 defect on thin stock. At the same time the Economy insole is an improvement on the Gem insole because of the greater strength of the marginal lip or rib and because the stock at both the inside and outside of the 60 tip is of the same thickness, making for a tighter seam and for less damage to the reinforcing fabric during the inseaming operation, as is well understood by those skilled in the art. Another, and a serious, 65 defect in the Gem insole, which the latter types of reinforced insoles overcome, is that the duck or canvas, used as reinforcing fabric, is trimmed in such manner that its raveled edge shows beyond the edge of the insole 70 and gives an unsightly appearance to the inside of the finished shoe. It has more recently been proposed to combine some of the good features of the Economy and Gem insoles in a single insole and some manufacturers are now using an insole blank having a marginal lip or rib like that of the Economy insole and a sheet of reinforcing fabric applied thereto like that of the Gem insole. An illustration of this type is found in Figure 80 3 of the Thoma Patent No. 1,108,026, dated August 18, 1914. Still this reinforced insole, which may be termed the "Cincinnati" insole is imperfect because it does not overcome the serious defect of the fabric showing, at the shank of the insole especially, in the finished shoe.

The object of the present invention is to improve the manufacture of insoles in such manner as to produce a reinforced insole 90 which overcomes all the defects hereinbefore adverted to as present in insoles of this general type.

To the accomplishment of this object the invention consists in the method of making 95 reinforced insoles, the preferred manner of practising which is hereinafter described and defined in the appended claims.

An understanding of the invention will be assisted by reference to the accompanying drawing in which,

Fig. 1 is a transverse section across the forepart of an insole blank with its edge slit as is customary in making a Gem insole; Fig. 2 is a transverse section across 105 the forepart of the insole blank of Fig. 1 with the marginal lip upstanding and reinforcing fabric applied to its lipped face;

and Fig. 3 is a transverse section across the shank of the insole of Fig. 2 after having been operated on by the present novel method.

- 5 In making the insole, the blank 2 which may be of leather or any other suitable material, is preferably slit at its edge as at 4 (Fig. 1) in a plane usually parallel to the face of the blank. The section 6, on the 10 flesh side, if the blank is of leather, is then upturned to form a marginal lip or rib (see Fig. 2) while the section 8, on the opposite or grain side of a leather blank, forms the feather of the insole. Reinforcing fabric 15 10 which is preferably, although not necessarily, in the form of a wide sheet is then applied to the lipped face of the blank 2, being beaded or crimped about the lip or rib 6 and extending laterally to either side 20 thereof. The fabric may be applied by hand, or by any of the commercial machines supplied for performing this operation, and if applied by a machine the fabric, if it projects beyond the edge of the blank, may 25 be simultaneously trimmed along a line coinciding with the edge of the blank, as shown in Fig. 2. It will be understood that the reinforcing fabric, now generally used, is of the "prepared" type, that is, provided 30 with a cementitious coating which when cool is dry but which becomes tacky when heated, and it is applied to the blank while in its heated condition. The first application of the fabric seldom causes the fabric to lie 35 snugly in the angles at the outer and inner sides of the lip or rib and, therefore, a rib tightening operation on the reinforced blank is very generally performed. The machine of application Ser. No. 822,757 is preferably 40 used to perform this rib-tightening operation and the insole is passed through this machine while the fabric is still hot, that is, before the cementitious coating has had time to become set and hold the fabric firmly to 45 the blank. This rib tightening machine has tools for pressing on the fabric in the angles at both sides of the lip or rib and causing it to lie snugly against the blank at these points. The rib tightening tools are 50 also so shaped as to give the reinforced lip or rib an inward set or bend, as shown in Fig. 3 for a purpose hereinafter explained. Furthermore, this rib tightening machine is provided with means to consolidate the 55 stock at the inside of the lip or rib, forming a channel at this point, as shown at 12, (Fig. 3), and reducing the stock just inside the lip to the same thickness as the feather. The rib tightening tool for operating in the 60 angle between the lip and feather, in tucking the fabric tightly into the outside angle, acts to draw the fabric slightly within the edge of the blank, as shown at 14 (Fig. 3). This is an advantageous way of removing 65 the fabric from the marginal portion of the

feather as it leaves the feather unreduced from the thickness which existed before the application of the fabric and, therefore, unweakened. Those skilled in the art will recognize however, that there are other ways 70 of removing the reinforcing fabric from the outer margin of the feather, all, except as it may be specifically defined in one or more of the appended claims, it is not essential that this step in the production of the novel 75 insole be performed by said rib tightening machine.

As a result of this method of making reinforced insoles the insole produced is possessed of all the features of advantage hereinbefore adverted to, namely; the lip or rib is sufficiently strengthened, for receiving the inseam, by two layers of fabric; the stock at both sides of the lip or rib is of the same thickness, providing for a tight 80 seam; the fabric is removed from the outer margin of the feather so that it is not visible when the insole is attached to the upper; and the lip or rib is bent inwardly so as to provide a firm support for the 85 channel guide of the welt sewing machine and enable the shoe to be easily held in proper position to receive the inseam 90 stitching.

I believe myself to be the first to devise 95 a method of making reinforced insoles in which the reinforcing fabric is so applied and shaped as to render it invisible after the insole has been incorporated in a shoe, and especially in so carrying out this method 100 that the feather of the insole is left unreduced from the thickness which existed before the application of the reinforcing fabric. The shank portion of the insole is its only portion plainly visible on looking 105 into the completed shoe, and, therefore, it will be obvious that the fact that the reinforcing fabric on parts of the insole other than the shank is or is not invisible is immaterial, the true scope of the invention being 110 found defined in the appended claims.

Having thus described the invention and the preferred method of practising it, what is claimed as new is:

1. The method of making reinforced insoles which comprises providing a blank with a marginal, upstanding lip or rib and outside feather portion, applying reinforcing fabric to the lipped face of the blank, and removing the fabric from the outer margin of the feather portion, at the shank portion of the blank at least and without reduction of the thickness of the feather, to cause its edge to lie within the edge of the blank. 115

2. The method of making reinforced insoles which comprises edge slitting a blank, upturning one of the two sections to produce a lip and feather, applying reinforcing fabric to the lipped face of the blank, and 120 125 130

- removing the fabric from the outer margin of the feather, at the shank portion of the blank at least and without reduction of the thickness of the feather, to cause its edge to lie within the edge of the blank.
3. The method of making reinforced insoles which comprises edge slitting a blank, upturning one of the two sections to produce a lip and a feather, applying reinforcing fabric to the lipped face of the blank, bending the lip inwardly, and drawing the fabric inward across the feather into the angle outside the lip until its edge lies within the edge of the blank.
- 15 4. The method of making reinforced insoles which comprises cutting the marginal portion of a blank to produce a lip and a feather, applying reinforcing fabric to the lipped face of the blank, consolidating the stock in the angle inside the lip, and drawing the fabric inward across the feather into the angle outside the lip until its edge lies within the edge of the blank.
- 20 5. That step in the manufacture of reinforced insoles which consists in removing the previously applied reinforcing fabric from the outer margin of the feather without weakening the feather by reducing its thickness.
- 25 6. That step in the manufacture of reinforced insoles which consists in drawing the margin of the reinforcing fabric, previously applied to the feather of an insole blank, inwardly until its edge lies on the feather within the edge of the blank.
- 30 7. That step in the manufacture of reinforced insoles having reinforcing fabric extending over the lip and across the feather which consists in tucking the fabric into the angle outside the lip and causing its edge to be drawn within the edge of the insole blank.
- 35 8. The method of making reinforced insoles which comprises providing a blank with a marginal, upstanding lip or rib, making an incomplete application of reinforcing fabric to the lip or rib, trimming the fabric along a line such that when completely applied its edge will lie within the edge of the blank, and then completing the application of the fabric.
- 40 9. The method of making reinforced insoles which comprises partially applying reinforcing fabric to a lipped insole blank at the opposite sides of the lip thereof, trimming the fabric, and thereafter completing the application of the fabric by drawing it into the outside angle between the lip and feather to a position with its edge lying on the feather within the edge of the blank.
- 45 10. The method of making reinforced insoles which comprises providing a blank with a marginal, upstanding lip or rib and outside feather portion, applying reinforcing fabric to the lipped face of the blank, and removing the fabric from the outer margin of the feather portion, at the shank portion of the blank at least, to cause its edge to lie within the edge of the blank.

JAMES E. JACKSON.
